UNITED STATES PATENT OFFICE

132,949

DESIGN FOR A CHOCOLATE CONFECTION

James F. Cyphers, Milton, Mass., assignor to
Walter Baker & Company, Inc., New York, N. Y.,
a corporation of Massachusetts

Application April 8, 1942, Serial No. 106,497

Term of patent 14 years

To all whom it may concern:

Be it known that I, James F. Cyphers, a citizen of the United States, residing at Milton, county of Norfolk, State of Massachusetts, have invented a new, original, and ornamental Design for a Chocolate Confection, of which the following is a specification, reference being had to the accompanying drawing, forming part thereof.

Figs. 1 and 3 are side views;

Fig. 2 is a top view; and
Fig. 4 is a perspective view of the chocolate confection, showing my new design.

I claim:

The ornamental design for a chocolate confection as shown.

JAMES F. CYPHERS.
